UNITED STATES PATENT OFFICE

93,808

DESIGN FOR A SHOE

Benjamin Batterman, New York, N. Y.

Application August 24, 1934, Serial No. 53,051

Term of patent 3½ years

To all whom it may concern:

Be it known that I, BENJAMIN BATTERMAN, a citizen of the United States of America, residing in Manhattan, county of New York and State of New York, have invented a new, original, and ornamental Design for a Shoe, of which the following is a specification, reference being had to the accompanying drawing, forming part thereof, wherein,

Figure 1 is a plan view of a shoe, showing my new design.

Figure 2 is a side elevational view of the shoe, shown in Figure 1.

The characteristic feature of my new design

resides in the effect caused by arranging two parallel rows of eyelets, on opposite sides of the lace-stays of the shoe, the said inner rows of eyelets on either side of the lace-stays being parallel and directly horizontal to each other, while the two outer rows of eyelets being located higher up on opposite sides of the lace-stays than the inner rows of eyelets, the said outer eyelets also being horizontal to each other.

I claim:

The ornamental design for a shoe, substantially as shown and described.

BENJAMIN BATTERMAN.
